[57] CLAIM

The ornamental design for a skid steer loader, as shown and described.

DESCRIPTION

FIG. 1 is a perspective view of our new design for a skid steer loader and shows the boom and bucket in the lowered position, the broken lines showing a bucket attachment are for illustrative purposes only and form no part of the claimed design;

FIG. 2 is a side elevational view of the skid steer loader shown in FIG. 1, the boom and bucket being shown in a raised position;

FIG. 3 is a side elevational view of the skid steer loader shown in FIG. 1, the boom and bucket being shown in the lowered position;

FIG. 4 is a front view of the skid steer loader shown in FIG. 1, the broken lines showing a bucket attachment are for illustrative purposes only and form no part of the claimed design; and,

FIG. 5 is a rear elevational view of the skid steer loader shown in FIG. 1.
